UNITED STATES PATENT OFFICE.

ERNEST CADGENE, OF ENGLEWOOD CLIFFS, AND GEORGE DUPONT, OF PATERSON,
NEW JERSEY.

METHOD AND MACHINE FOR PRINTING FABRICS

Application filed October 25, 1923. Serial No. 670,670

This invention relates to fabric printing machines of the type disclosed in our Patent No. 1,480,348, dated Jan. 8, 1924, which machines produce a raised or bas-relief ornamentation upon the fabric by means of a perforated stencil, through which a printing composition of a thick pasty consistency is fed to the fabric.

10 In the machines of this type as heretofore constructed by others, it has been possible to produce only single colored ornamentalations, by one running of the fabric through the machine and while multi-colored effects and designs employing the bas-relief stencil 15 ornamentation as a part thereof have been heretofore produced, they have only been produced by hand labor and consequently have not been extensively used because of the resultant high costs of production.

20 The principal object of this invention is to provide a new and improved construction of a machine capable of performing in a single running of the fabric through the machine, a printing of a bas-relief ornamentation with one or more perforated stencils 25 in connection with or supplementary to a

printing of a flat ornamentation with the one or more of the usual solid printing rolls. Another object is to so construct the machine that the line contacts against the pressure roller of the several printing devices employed, may be adjusted so as to secure an accurate registration of the component parts of the finished design.

35 For the accomplishment of these and such further objects as will be apparent to those skilled in the art to which this appertains, the invention consists in the construction, combination and arrangement of parts and 40 embodiment of which is hereinafter more specifically described and is illustrated in the accompanying drawings forming a part hereof, but it will be understood that changes, variations and modifications may be 45 resorted to without departing from the spirit of our invention.

In the drawings:

Fig. 1 is a central longitudinal section through a machine, embodying our invention.

Fig. 2 is a section on the line 2-2 of Fig. 1.

Fig. 3 is an enlarged side elevation of the stencil printing means.

55 Fig. 4 is an enlarged side elevational de-

tail of the means for adjusting a solid printing roll.

Fig. 5 is a sectional view therethrough.

Fig. 6 is a diagrammatic illustration of a

sample of the work printed in the machine. 60
As shown in the drawings, the numeral 10 indicates generally the frame of the machine on the front side of which is mounted the feed roller 11, containing the fabric to be printed, which is led therefrom about an idler roll 12, and thence about a large pressure roller 13 against which the solid printing roller 14 and stencil 15 engage. 65

The pressure roller 13 is rotatably mounted in bearings 16 slidably mounted in suitable guides in the frame 10 and screws 17 are provided for the vertical adjustment of the bearings and roller to regulate the printing pressure. Any suitable driving means such as the pulley 18 and belt 19 leading to a convenient source of power may be employed for driving the roller 13. 70 75

The solid printing roll 14 is keyed, as at 20, to the shaft 21 and is provided at one end with a driving flange 22 apertured to receive the bolts 23 which pass through the arc shaped slots 24 provided in a driving gear 25 which meshes with a large gear 26 secured to the pressure roller 13. Means are provided for adjusting the pressure of the printing roller 14 against the pressure roller 13 and for this purpose the shaft 21 is mounted in the bearings 50 which are slidably mounted in suitable guideways 51 formed in the frame 10. The pressure screws 52 engage with the upper faces of said bearings to force the printing roller into printing contact with the fabric and the compression springs 53 are provided for moving the roller 14 away from the pressure roller 13 when the screws 52 are released.

The construction of the stencil 15, the mounting thereof, and the means for feeding the printing paste or composition therethrough, is similar to that shown in the above mentioned patent and a brief description thereof will suffice for the purposes of this application. 100

The stencil 15 is mounted for free floating rotation upon a non-rotatable support preferably in the form of a hollow drum 27 which has its outer ends clamped between a clamping device, the lower half 28 of which is formed in a bracket 29, suitably secured to the frame 10, and the upper half 30 of which

is detachably secured to the lower half by means of the bolts 31. A portion of the lower part of the drum 27 is cut out, as at 37, to permit a combined pressure element and distributing blade 33 to contact with the inner circumference of the stencil and hold it against the pressure roller 13. The pressure element 33 is provided with trunnions 34 removably mounted in the split bearings 35 formed in brackets 36 adjustably bolted to the sides of brackets 29, and to the projecting ends of said trunnions, are secured the lever arms 37, upon which the weights 38 are adjustably mounted for holding the pressure element 33 with a yielding constant pressure against the pressure roller 13.

10 15 A pipe 39, which is connected with a suitable reservoir, (not shown) containing a supply of printing composition for the stencil 15, extends into the drum 27 and is provided with a plurality of nozzles 40, which deliver the printing composition to a trough 41, mounted within the drum 27 and extending the full length thereof. The trough 41 20 25 is provided with a foraminated bottom through which the printing composition flows to a deflector plate 42, the lower edge of which terminates adjacent the lower edge of the pressure element 33.

30 Printing composition is supplied to the roller 14 by any suitable means such as the inking roller 43 mounted in the lower end of ink fountain 44.

In the operation of the machine, the fabric 35 passes from the feed roll 11 around the idler roll 12 and between the printing roller 14 and pressure roller 13. The printing roll 14 is provided with any suitable design as for example the leaves 46 (Figs. 2 and 6) 40 which are cut into the roller or which may be formed in an electrotype detachably secured to said printing roll in accordance with the well known constructions of devices of this character. After the design on 45 roller 14 has been printed, the fabric passes between the stencil 15 and the pressure roller 13 to receive a second printing of the characteristic bas-relief ornamentation produced by this type of printing. In the design 50 shown in Fig. 6 the leaves 46 are outlined or surrounded by a plurality of raised dots 47.

At the beginning of the printing operation, the printing roll 14 and stencil 15 are set to insure proper registration of the ornaments with one another, which may be done by raising levers 37 to release the pressure of pressure element 33 on the stencil and then shifting the stencil about drum 27 or the setting of the pressure roller 14 may 60 be changed by loosening the bolts 23 and shifting the flange 22 and roller 14, relatively to the gear 25 or for larger adjustments withdrawing the roll 14 and gear 25 sufficiently from the pressure roller to shift 65 the gear tooth engagement of gears 25 and

26. After the printing by the stencil 15, the fabric is preferably led directly from the machine to a drying machine.

It will be understood that the diameters of the stencils and printing rollers employed 70 must be exact multiples of one another to cause the repetition of the designs or ornaments to fall upon the fabrics in exact superimposed relation or alignment and also that if any of the various printing stencils 75 and rollers contain only a single unit of a motif for the final design in a circumferential direction, the contact line of such printing member with the pressure roller 13, would have to be located at such a distance 80 from the contact line of the succeeding printing member as to cause the successive printings to be brought into proper registration.

While for the purpose of this application we have only shown one stencil 15 and printing roll 14, it will be obvious that any number of such printing devices could be employed in accordance with the number of colors which it is desired to reproduce in the finished product. 90

Having thus described our invention, what we claim as new and desire to secure by Letters Patent, is:

1. A machine for printing flat and bas-relief ornamentations on textile fabrics including a pressure roller, a pair of printing members one of which includes a thin perforated stencil mounted above and capable of contact with said pressure roller, and the other printing member including a printing roller mounted adjacent said pressure roller and in advance of said stencil in accordance with the direction of movement of a fabric through the machine, a shaft for said printing roller on which the roller is secured, a gear on said shaft, cooperating means between said printing roll and gear permitting a peripheral adjustment of the roller relative to said stencil, and a second gear on said pressure roller engaging the first named gear to drive said printing roller directly from said pressure roller. 100 105 110

2. A machine for printing flat and bas-relief ornamentations on textile fabrics including a pressure roller, a pair of printing members one of which includes a stencil mounted above and capable of contact with said pressure roller, and the other printing member including a printing roller mounted adjacent said pressure roller and in advance of said stencil in accordance with the direction of movement of a fabric through the machine, a shaft for said printing roller on which the roller is secured, a gear on said shaft and with respect to which said roller has an axial adjustment, a flange carried by said printing roller and engageable with a face of said gear, means extending through said gear and flange for securing said printing roller in various adjusted positions, and 115 120 125

a second gear on said pressure roller engaging the first named gear to drive said printing roller directly from said pressure roller.

3. A machine for printing flat and bas-
5 relief ornamentals on textile fabrics in-
cluding a pressure roller, a pair of print-
ing members one of which includes a stencil
mounted above and capable of contact with
said roller, and the other printing member
10 including a printing roller in engagement
with said pressure roller and mounted in ad-
vance of said stencil in accordance with the
direction of movement of a fabric through
the machine, a shaft for said printing roller,
15 supporting means for said shaft, means for
adjusting said supporting means to vary
the pressure of the printing roller against
said pressure roller, a gear on said shaft,
cooperating means between said printing
20 roller and gear permitting a peripheral ad-
justment of the roller relative to said stencil,
and a second gear on said pressure roller
engaging the first named gear to drive said
printing roller directly from said pressure
25 roller.

4. A machine for printing flat and bas-

relief ornamentals on textile fabrics, in-
cluding a frame having an inclined guide-
way therein, a pressure roller mounted in
said frame, a gear carried by said roller, a 30
bearing slideable in said guideway, a shaft
supported in said bearing, a spring inter-
posed between the inner end of said guide-
way and said bearing to force the latter
outwardly in said guideway and away from 35
said pressure roller, an adjustable screw en-
gageable with said bearing to adjust the
same toward said roller, a printing roller
keyed on said shaft and having a slotted
flange at its end, a gear engageable with said 40
flange and driven by the gear on said pres-
sure roller and with respect to which said
printing roller is axially adjustable, bolts
extending through the second named gear
and the slots in said flange to secure said 45
printing roller in adjusted positions, and a
stencil in contact with said pressure roller
for producing bas-relief ornamentals.

In testimony whereof we have affixed our
signatures.

ERNEST CADGENE.
GEORGE DUPONT.
